TOY WALKING DOG

Leon H. Kramer, Roxbury, Mass.

Application March 15, 1952, Serial No. 18,917

Term of patent 3½ years

(Cl. D34—2)

To all whom it may concern:

Be it known that I, Leon H. Kramer, a citizen of the United States, residing at Roxbury, in the county of Suffolk and State of Massachusetts, have invented a new, original, and ornamental Design for a Toy Walking Dog, of which the following is a specification, reference being had to the accompanying drawing, forming part thereof.

Fig. 1 is a plan view of a toy walking dog embodying my new design.

Fig. 2 is a side view thereof.

Fig. 3 is a front view thereof.

I claim:

The ornamental design for a toy walking dog, substantially as shown.

LEON H. KRAMER.
